CRANK PADDLE FOR BOATS

Fred Schwarzer, Rte. 18, Pottstown, Pa.

Filed Jan. 29, 1959, Ser. No. 789,888

7 Claims. (Cl. 115—67)

This invention relates to a boat propelling means and particularly to such means wherein the boat propelling means partake of true vertical movements with respect to the water surface upon which the boat is to travel, and it consists in the constructions, arrangements and combinations herein described and claimed.

It is the cardinal object of the invention to provide a boat propelling means wherein the propelling means under operation, enter and leave the water surface in a vertical path, thus eliminating churning and splashing of the water as is common in the present day rotary type propellers.

More specifically, it is an object of the invention to provide a boat propelling means wherein the propelling members are operatively mounted upon a support frame which may be readily secured upon a water craft, the propelling means being so constructed as to enter and leave the surface of the water in true vertical paths and in which the supporting frame for the propelling means is oscillatably mounted in a horizontal plane for steering of the water craft, and said supporting frame also being mounted for movement from an operative position in the water to an inoperative position within the water craft.

It is also an important object of the invention to provide a water craft propulsion means which may be electrically or manually actuated, the power from its source being transmitted to the propelling means either through gearing, V-pulleys and belts, thus enabling the propelling means to be employed in motivating toy boats, huntsmen's and fishermen's boats or otherwise.

Additional objects, advantages and features of invention will be apparent from the following description, considered in conjunction with the accompanying drawings, wherein,

Figure 1 is a fragmentary top plan view of a boat having the propelling means installed, illustrating the power means as being an electric motor, the control of which is illustrated diagrammatically.

Figure 2 is a longitudinal section of Figure 1.

Figure 3 is a section taken on the line 3—3 of Figure 2.

Figure 4 is a cross section taken on the line 4—4 of Figure 2.

Figure 5 is a cross section on the line 5—5 of Figure 4.

Figure 6 is a fragmentary longitudinal section through a boat, illustrating a pedal actuated means for activating the propulsion means.

Figure 7 is a top plan view thereof.

Figure 8 is a fragmentary sectional view of a boat illustrating a further form of manual operation for propelling a boat, and

Figure 9 is a fragmentary cross section on the line 9—9 of Figure 8.

In the drawings, the reference character 10 designates the boat generally, which may be constructed from any

2

suitable materials and of the required specifications as to construction, size or other requirements as found necessary.

Attention is now invited to Figures 1 and 2 of the drawings, wherein the power propulsion means is shown as an electric motor 11 mounted upon the floor or bottom wall 12 of the boat, the motor being longitudinally adjustable with respect to a drive pulley 13 on the driven shaft of the motor and a driven pulley 14 associated with 10 the propulsion means presently to be described.

A mounting plate 15 is secured upon the upper edge of the stern 16 of the boat, by suitable screws or other fasteners, as best seen in Figure 1, the plate 15 being located medially of the longitudinal axis of the boat and 15 has a semi-circular opening 17 formed therein. A transverse bar 18 integral with the opposed side walls of the opening 17 has a bearing opening 19 positioned axially of the semi-circular opening 17 for oscillatably mounting a yoke 20. The yoke 20 comprises a flat base 21 20 having upright spaced legs 22, the base having an opening 23 aligned with the opening 19 of the bar 18 and through these openings a pivot bolt 24 is secured. It should be noted that the base 21 is seated upon the bar 18 and that the yoke 20 is of such proportions as to be 25 freely oscillatable within the semi-circular opening 17 for a purpose as will be presently apparent.

The propulsion means for the boat is generally indicated at 25 and comprises a pair of parallel spaced elongated frame members 26 integrally connected by a top 30 wall 27 which is located intermediate the length of the frame members. The frame members 26 are downwardly inclined with respect to the forward end 28 thereof and the lower edges 29 of the frame members are 35 disposed horizontally with respect to the mounting plate 15 adapted to ride upon a semi-circular track 30 formed upon the upper face of the plate 15, for a purpose as will presently appear.

Each of the frame members 26 at the rear end are 40 provided with a vertical extension 31, the extensions being in opposed parallel relation and terminate in upper bearings 32 and lower bearings 33. In the upper bearings 32 a shaft 34 is journaled and mounts a gear 35 which is keyed to the shaft and is positioned adjacent one of the frame members 26 and held in such position by means of a hub 36 on the gear which engages the opposite frame member 26. In the lower bearings 33 a shaft 37 is journaled for similarly mounting a gear 38. Between the frame members 26 there are revolutely mounted respective gears 39, 40, 41 and 42 in meshed 45 engagement, but the gear 39 is additionally in mesh between gears 35 and 38. The gear 42 is mounted upon a shaft 43, as clearly shown in Figure 3, the gear including a V-pulley 44 formed integrally with the gear 42. From a further consideration of Figure 3, in conjunction 50 with Figures 1 and 2, it will be seen that the shaft 43 is mounted in the upright legs 22 of the yoke 20 and also mounts the arms 45 of a tiller 46; and further that the forward ends 28 of the frame members 26 are pivotally mounted upon the shaft 43, the gear 42 and pulley 44 being disposed between respective frame members.

The pulley 14 is of dual formation and is rotatably mounted in a yoke 47, the latter being secured upon the floor or bottom of the boat, the pulley 14 being driven by a belt 48 from the pulley 13 of the motor, while 55 pulley 14' is aligned with the pulley 44 which is driven by a belt 49.

The shafts 34 and 37 project beyond respective bearings 32 and 33, the shaft 34 having a pair of levers 50 keyed thereto, the levers being positioned upon opposite sides of the frame members 26 and extend in opposite directions at right angles to the shaft 34. A similar 60 pair of levers 50' are likewise secured to the shaft 37,

the outer ends of the levers 50 and 50' being formed for reception of a bearing pin 51 for pivotally mounting an arm 52, the lever 50 being pivotally connected to the upper end of the arm 52, while the lever 50' is pivotally connected to the arm 52 at a point above the scoop-like paddle 53 secured to the lower end of the arm 52.

Thus it will be seen that upon rotation of the gear train as described, a straight upward and downward movement of the paddles 53 will be effected, eliminating churning and splashing of the water, and it will also be noted that steering of the boat may be effected through actuation of the tiller 26 to oscillate the propulsion means upon the pivot bolt 24.

Obviously, various power means may be employed to actuate the gear train shown, and that illustrated in Figure 1 has been found highly practical in the operation of toy boats, the boat having been steered by any suitable remote control. Such controls, as well understood, comprise a case (not shown) for housing dry cells 54 and a control switch 55 which are in circuit with the motor 11.

In Figures 6 to 9, manual means are employed and this mode of operation has been especially designed for propulsion of row boats, canoes and the like and would appeal to sportsmen, such as fishermen and hunters, where a quiet propulsion of the craft may be desired, and obviously would be appealing to those who would use the boat as a means of exercise and recreation.

Referring in detail to Figures 6 and 7, a tubular frame structure 56 is shown, which consists of front and rear leg members 57 and 58 suitably supported upon the bottom or floor of the boat, the legs being connected by horizontally disposed portions 59 upon which a seat 60 is secured, these portions 59 likewise forming a support for the propulsion means 25'.

The front legs 57 of the frame structure are provided with parallel bearing plates 61 between which the hub 62 of a pedal crank 63 is mounted, the hub having a V-pulley 64 aligned with a V-pulley 65 of dual formation and keyed to a shaft 66 rotatably supported between brackets 67 connected between respective portions 59 and rear legs 58 of the frame structure. A V-belt 68 is trained about the pulley 64 and one of the pulleys 65. The drive from the dual pulley 65 is effected by means of a V-belt 69 trained about a pulley 70 of a dual pulley assembly of the propulsion means 25'; and the final drive to the paddles 53' is by way of a V-belt 71 trained about the other pulley of the dual assembly 70 and a V-pulley keyed to the shaft 72 which likewise supports gear 39' which is in mesh with gears 35' and 38'. Guide pulleys 73 are provided for support of respective reaches of the belt 71.

In the drive shown in Figures 8 and 9, the operator assumes a standing position and to this end the frame structure 74 has an elevated rear support 75 for the propulsion means 25'' and a lower forward support 76 which consists of a pair of parallel members 77, each of which are formed with an upper bearing 78 and lower bearing 79. Between the upper bearings a crank shaft 80 for support of a V-pulley 81 is rotatably mounted, the ends of the crank shaft being engaged in respective slots 82 formed in a pair of spaced upright actuating handles 83, the lower ends of which are oscillatably mounted upon a shaft 84. A V-belt 85 is trained about pulley 81 and a pulley of a dual pulley assembly 86, and from the latter pulley a belt 87 transmits rotation to a pulley 88 of the power propulsion means 25''.

From the foregoing, it will be seen that a boat propulsion means has been provided which is efficient in operation, of light weight for installation and removal; readily movable to operative position within the water and is also movable to an inoperative position within the boat, as indicated in dotted lines in Figure 2.

While I have shown and described preferred forms of the propulsion means, this is by way of illustration only, and I consider as my own all such modifications in con-

struction as fairly fall within the scope of the appended claims.

I claim:

- 5 1. In a propulsion means for boats comprising a frame member, a series of interconnected power transmitting means carried by the frame, a pair of said power transmitting means being positioned in a vertical plane one above the other with respect to the body of water upon which the boat is to be propelled, a pair of levers operatively connected to said pair of power transmitting means at opposite sides of the frame, a paddle member connected to the lower end of an arm connected between the pair of levers upon respective sides of said pair of power transmitting means, means for motivating the power transmitting means, and said frame member being mounted upon the boat for horizontal oscillatory movements and having means for so oscillating the frame member.
- 10 2. The structure of claim 1, wherein said frame member is further pivotally mounted for movement from the body of water into a position within the boat.
- 15 3. In a propulsion means for boats comprising a frame member having means for securement to a boat and having oscillatory movements in a horizontal plane, a series of interconnected power transmitting means carried by the frame, a pair of said power transmitting means being positioned in a vertical plane one above the other with respect to the body of water upon which the boat is to be propelled and having respective shafts projecting beyond the sides of the frame, a lever connected to respective ends of the shafts, the levers on each shaft being extended in opposite directions at right angles to each other, an arm connected to the levers at respective ends of the shafts, water engaging paddles on the lower ends of said arms and means for motivating said power transmitting means.
- 20 4. In a propulsion means for toy boats comprising a frame member having means for securement to the stern portion of a boat, said means having oscillatory movements in a horizontal plane, a series of interconnected power transmitting means carried by the frame, a pair of said power transmitting means being positioned in a vertical plane, one above the other with respect to the body of water upon which the boat is to be propelled, said pair of power transmitting means having respective shafts projecting upon opposite sides of the frame, a lever connected to respective ends of the shafts, the levers on each shaft being extended in opposite directions at right angles to each other, an arm connected to the levers at respective ends of the shafts, water engaging paddles on the lower ends of said arms, an electric motor mounted within the boat including means for motivating said interconnected power transmitting means and remote control means for said motor.
- 25 5. In a propulsion means for boats, a frame member comprising a pair of parallel side members having opposed upright extensions at the rear end thereof and a yoke member at the front end of said side members for oscillatably mounting the frame member upon a boat and positioning said rear end exteriorly of the boat, interconnected power transmitting means rotatably supported between said side members, a pair of said transmitting means being positioned adjacent the upper and lower ends of said upright extensions, said pair of power transmitting means having respective shafts projecting upon opposite sides of the upright extensions, a lever connected to respective ends of the shafts, the levers on each shaft being extended in opposite directions at right angles to each other, an arm connected to the levers at respective ends of the shafts, water engaging paddles on the lower ends of said arms, and manual operating means within the boat and operatively connected to the innermost power transmitting means.
- 30 6. The structure of claim 5, in which the manual operating means comprises a seat within the boat for the opera-

tor and a pedal drive to said innermost power transmitting means.

7. The structure of claim 5, in which the manual operating means comprises oscillatable levers mounted within the boat and operatively connected to a pulley for rotating the same and belts and pulley members connected with

said first pulley and the foremost power transmitting means.
